VIBRATOR TYPE MULTIPLE-SHOT
BLASTING UNITFrank C. Gibson, Broughton, Pa., and Frederick
W. Brown, Los Angeles, Calif.

Application July 15, 1947, Serial No. 761,125

10 Claims. (Cl. 171—97)

(Granted under the act of March 3, 1883, as
amended April 30, 1928; 370 O. G. 757)

1

The invention described herein may be manufactured and used by or for the Government of the United States for governmental purposes without the payment to us of any royalty thereon in accordance with the provisions of the act of April 30, 1928 (Ch. 460, 45 Stat. L. 467).

This invention relates to a blasting unit and, more particularly, to a multiple shot blasting unit for detonating simultaneously a plurality of explosive charges.

In mining operations it is sometimes less safe to fire a number of blasts one at a time than to fire all simultaneously. When this situation occurs, it is desirable to have available a small portable blasting unit that is convenient to use, capable of detonating a multiple charge, and safe to operate in a gaseous atmosphere.

It is an object of this invention to provide a blasting unit capable of detonating simultaneously a plurality of blasts connected in series.

It is an object of this invention to provide a blasting unit that is safe, reliable and may be used in underground mining operations where gas ignition hazards exist.

It is also an object of this invention to provide a blasting unit which is portable, durable, relatively inexpensive and simple to operate.

It is a further object of this invention to provide a blasting unit, the primary source of energy of which is a small battery such as a miner's cap lamp battery.

The foregoing and other objects will become apparent from the following specification taken in connection with the drawing which shows a schematic view of a blasting unit embodying the principles of this invention.

Input terminals 10 and 11 are provided to which may be attached a small battery 12 such as a miner's cap lamp battery. Terminal 10 is connected to blade 14 of double-pole, double-throw switch 15. Terminal 11 is grounded. Switch 15 also includes blade 16. Blades 14 and 16 are ganged for simultaneous operation and are biased in a normal position by spring 18. Blade 14 in its normal position engages a contact not otherwise connected in the circuit. In the operated condition of switch 15 blade 14 engages contact 17 connected to the mid point of primary 20 of transformer 21.

Transformer 21 is interconnected with vibrator 25 to provide a power supply for the blasting unit. Vibrator 25 comprises a grounded vibrating reed 26 which is caused to vibrate by magnet coil 27. Vibrator 25 also includes contacts 28, 30, 31 and 32, contacts 29 and 31 being on one side of said

reed 26 and contacts 30 and 32 being on the other side thereof. Vibrating reed 26 at one extreme of its vibrating cycle engages contacts 29 and 31 and at the other extreme of said cycle engages contacts 30 and 32. The end terminals of primary 20 are connected to contacts 29 and 30. The secondary 23 of transformer 21 has a center tap which is connected to ground through voltage dividing resistor 35. The end terminals of secondary 23 are connected to contacts 31 and 32. A resistor 36 and a condenser 37 are connected in series across the end terminals of secondary 23.

Blade 16 of switch 15 in the normal position of switch 15 is connected through a resistor 38 to ground. In the operated position of switch 15 blade 16 is connected to an adjustable tap on resistor 35. Blade 16 is connected to a contact 39 of switch 40. Switch 40 is similar to switch 15 being a double-pole, double-throw switch including blades 41 and 42 which are ganged for simultaneous operation and which are biased to a normal position by spring 44.

In the normal position of switch 40 blade 41 engages contact 39 and is thus connected to blade 16 of switch 15. In the operated position of switch 40 blade 41 engages contact 45 which is connected to contact 46 of switch 40. Blade 42 in the unoperated condition of switch 40 engages contact 41. In the operated condition of switch 40 blade 42 engages contact 46. Condenser 49 and gaseous glow lamp 50 are connected in parallel and across blade 41 and contact 47 of switch 40. Contact 47 is connected to ground. Blade 42 of switch 40 is connected to output terminal 51. The other output terminal 52 is connected to ground.

A plurality of explosive charges or blasts 54 and 55 each including electrical detonating means 56 and 57, respectively, may be connected to output terminals 51 and 52 with the detonating means 56 and 57 connected in series.

In the operation of the device described above a battery 12 is connected to input terminals 10 and 11 and a series of electrical detonators such as 56 and 57 associated with explosive charges 54 and 55, respectively, are connected in series between output terminals 51 and 52. It will be understood that a greater number of explosive charges may be placed in series with the output terminals 51, 52 than are shown in the drawing.

When switch 15 is in its normal unoperated position, blade 14 of switch 15 engages an otherwise unconnected contact so that battery 12 is effectively isolated from the blasting unit circuit. When switch 40 is in its normal or unoperated position condenser 49 is discharged through blade

41 and contact 39 of switch 40 through blade 16 of switch 15 and resistor 38 while output terminal 51 is connected to ground through blade 42 and contact 47 of switch 40 thus shorting output terminals 51 and 52.

When switch 15 is operated, blade 14 engages contact 17 applying the relatively low potential of battery 12 through part of the primary 20 of transformer 21 and across vibrator coil 27. Vibrator reed 26 is then attracted toward coil 27 to engage contacts 29 and 31. The engagement of reed 26 with contact 29 shorts coil 27 cutting down the attraction thereof for reed 26 and allowing reed 26 to swing back past its mid position to engage contacts 30 and 32. Immediately 15 on the breaking of the engagement between contact 29 and reed 26 coil 27 begins to build up an attraction for reed 26 causing this reed to eventually swing back to engage again contacts 29 and 31. This cycle is continuously repeated, the natural period of reed 26 being designed for the frequency of vibration desired.

It will be seen that as reed 26 engages first contact 29 and then contact 30 that an alternating flux will be set up in primary 20 of transformer 21 to induce an alternating voltage in secondary 23. This alternating voltage will be rectified as reed 26 alternately engages contacts 31 and 32 to provide a relatively high direct current voltage across resistor 35. Buffing condenser 37 is connected in series with resistor 36 across the end terminals of secondary 22 to give the proper wave form for long vibrator life. Resistor 36 is used to protect the transformer in case of failure of condenser 37.

With switch 15 in its operated position the adjustable tap along resistor 35 picks up a voltage therefrom which is applied through blade 16 of switch 15 and through contact 39 and blade 41 of switch 40 to condenser 49 which is charged thereby. As the condenser 49 becomes charged its potential rises and when the condenser is substantially fully charged a sufficient potential is applied across glow tube 50 to cause it to glow. A resistor 48 in series with glow lamp 50 properly limits the current through the glow lamp. The lighting of lamp 50 shows condenser 49 to be adequately charged and in good condition and indicates generally that the unit is functioning properly.

To fire the explosive charges, switch 40 is operated. Operation of switch 40 disconnects blade 42 from contact 47, thus removing the short across output terminals 51 and 52, and connects condenser 49 through blade 41, contacts 45 and 46, and blade 42 of switch 40 to the electrical detonators 56 and 57 of explosive charges 54 and 55, respectively to detonate these explosive charges, the circuit being completed through the ground connected to contact 47 and terminal 52. The firing cycle can be stopped at any time during charging by allowing switch 15 to return to its unoperated position which discharges condenser 49 through resistor 38.

Vibrator 25 is completely enclosed by a shielding can 33. Any sparks produced at the vibrator contacts during operation of the vibrator are effectively isolated by shielding can 33 from the atmosphere in which the unit is operated. Can 33 also protects the vibrator during handling. To prevent operation of the unit by accident, switches 15 and 40 should be recessed into the case. It is preferable that the entire blasting unit be enclosed in a waterproof container and sealed to prevent unauthorized tampering.

It will be seen that this invention provides a portable, durable, relatively inexpensive multiple shot blasting unit which is simple to operate, requires minimum maintenance and has no periodical component replacement. The cap lamp battery required as a primary source of energy is used by underground mine workers in nearly all mines. This battery is almost universally available and it is common practice for it to be recharged daily. The cap lamp battery is therefore a reliable and convenient source of energy for a miner's blasting unit. The capacity of condenser 49 as well as the potential picked up by the adjustable tap or resistor 35 and applied to condenser 49 is selected to produce a combination which will provide adequate energy to fire the electric blasting caps and still limit the time duration of the impulse to meet safety requirements.

In practice the complete firing cycle requires approximately three seconds and requires only the initial operation of switch 15 until the glow lamp 50 glows and then operation of switch 40 to fire the charges. The blasting unit will operate successfully from a 4-volt cap lamp battery and may safely be used in a gaseous atmosphere to fire ten detonators in series. The unit herein described when slightly modified can be used to initiate 100 or more electric blasting caps in series in blasting operations where conformance to rigid safety regulations is not required.

It will be understood that the embodiment of the invention described above is exemplary only and that many modifications within the scope of the appended claims will occur to those skilled in the art.

What is claimed is:

1. In combination a first switch connected between an input and a means for multiplying voltage, said first switch connecting said input to said voltage multiplying means only when said first switch is operated, a second switch connected to said voltage multiplying means, a condenser and an output, said second switch in its normal position acting to connect said condenser to said voltage multiplying means and said second switch in its operated condition acting to connect said condenser to said output.

2. The combination of claim 1, in which the voltage multiplying means includes a vibrator interconnected with a transformer.

3. The combination of claim 1, in which the voltage multiplying means comprises a vibrator interconnected with a transformer having a primary and a secondary, whereby the vibrator interrupts the voltage applied to said primary and rectifies the voltage derived from said secondary.

4. The combination of claim 1, in which a gas-filled glow tube is connected across said condenser to indicate the charge therein.

5. The combination of claim 1, in which said first and second switches are interconnected so that when said first and second switches are in their unoperated position said condenser is discharged.

6. The combination of claim 1, in which a battery is connected to said input.

7. The combination of claim 1, in which a battery is connected to said input and an electrical detonating device is connected to said output.

8. The combination of claim 1, in which a battery is connected to said input and a plurality of electrical detonating devices are connected in series across said output.

9. The combination of claim 1, in which said

second switch in its normal position also acts to short-circuit said output.

10. In combination, an input connected to a first switch means which only in its operated condition connects said input to a vibrator and transformer which are interconnected so as to multiply and rectify a voltage applied to said input to produce a relatively high unidirectional voltage, a second switch means connected in its normal position through a resistance to ground and connected in its operated position to at least a part of said unidirectional voltage, means to cause said first and second switch means to operate in synchronous and ganged relation, a condenser, a gas glow tube in series with a resistor connected across said condenser, a third switch means connected in its normal position to said second switch means, and in its operated position to a fourth switch means when the fourth switch means is in its operated position, said fourth switch means being connected in its normal position to one plate of said condenser, said third switch means being always connected to the other

5 plate of said condenser, said fourth switch means being always connected to an output, and means to cause said third and fourth switch means to operate in synchronous and ganged position.
